Primary Examiner — Mary Ann Calabrese(74) *Attorney, Agent, or Firm* — William H. Dippert; Eckert Seamans Cherin & Mellott, LLC(57) **CLAIM**

The ornamental design for a “magnetic display board,” as shown and described.

DESCRIPTION

FIG. 1 is an isometric view of a magnetic display board according to the present invention, wherein the small circles represent magnets;

FIG. 2 is a front view of the magnetic display board according to the present invention;

FIG. 3 is a rear view of the magnetic display board according to the present invention, wherein the smaller circles represent magnets;

FIG. 4 is an enlarged top view of the magnetic display board according to the present invention;

FIG. 5 is an enlarged bottom view of the magnetic display board according to the present invention;

FIG. 6 is an enlarged side view of the magnetic display board according to the present invention, wherein the opposite side is identical thereto; and,

FIG. 7 is an isometric view of the magnetic display shown in FIG. 1, with the transparent sheet partially removed.

The present invention is a magnetic display board mainly adapted for displaying an ad, announcement, a flyer, or such between a board and a transparent sheet. The board and the transparent sheet are provided with corresponding magnets. The broken lines represent openings in the display board, and form no part of the claimed design.
